BENJAMIN FRY DALY, OF NEW YORK, N. Y.

ICE-TANK.

SPECIFICATION forming part of Letters Patent No. 766,600, dated August 2, 1904.

Application filed April 15, 1903. Serial No. 152,681. (No model.)

To all whom it may concern:

Be it known that I, BENJAMIN FRY DALY, a citizen of the United States of America, and a resident of the borough of Brooklyn, city of New York, county of Kings, State of New York, have invented certain new and useful Improvements in Ice-Tanks, of which the following is a specification.

This invention relates to ice-tanks; and its object is the production of tanks in which ice can be economically frozen and from which it can be easily removed without fracture.

Referring to the drawings, Figure 1 represents a plan view of my tank with its appurtenances. Fig. 2 shows a partial section of Fig. 1 on the line *x x*. Fig. 3 is a partial section of Fig. 2 on the line *y y*. Fig. 4 represents a partial section of Fig. 2 on the line *t t*. Fig. 5 shows a partial front view of Fig. 1 with a section of an air fore-cooler added thereto.

The tank is shown at *A* and is divided into sections *B* by the air-tight cells *D*. Water to be frozen is introduced into the sections *B*, and the cells *D* contain suitable means for circulating a refrigerant. The tank *A* comprises the bottom plate *a*, back plate *a²*, and a plate at each end, as *a'*. The cells *D* are formed with the plates *d*, extending from the plates *a* and *a²* of the tank, the front plates *a³*, and covers *d'*.

A pipe *E*, conveying a refrigerant, connects with the coils *E'*, contained in the cells *D*. The said coils at their lower ends connect with the pipe *E²*, which latter leads to a coil *E³*, contained in an air fore-cooler *F*, and from the coil *E³* there extends the pipe *E⁴*. A by-pass pipe *K* with valves *f*, *f²*, *f³* is connected with the pipes *E²* and *E⁴*.

Combined supports and division-plates *H* carry the coils *E'* and divide the cells *D* into sections *d²*, *d³*, *d⁴*. The said supports *H* are made in halves *h*, and at the junction of the said halves are formed apertures *h'* for the convolutions of the coils *E'* and apertures *h²* to connect the sections *d²*, *d³*, *d⁴*. Rivets *h³* connect the halves of the plates *H* and cells *D* together. Stuffing-boxes *I*, *I'* are secured to the plates *a³* of the cells *D* for the ends of

the coils *E'*. Suitable valves *e* and *e²* are connected to the pipes *E* and *E²*.

An air-pipe *G* enters the fore-cooler *F* and has connected therewith the valve *G⁵*. An outlet-pipe *G'* extends from the fore-cooler 55 and is connected with the pipes *G²*, having perforations *g*, the said pipes *G²* being supported in the cells *D*. Pipes *G³*, with perforations *g'*, are located in the lower portions of the cells and connect with a pipe *G⁴* on the 60 outside of the tank. Valves *e³*, *e⁴* are connected with the pipes *G'* and *G⁴*.

My invention may be modified by dispensing with the supports *H* and allowing the plates *d* of the cells *D* to hug the coils *E'*. 65

To operate my invention, the sections *B* of the tank are filled with the liquid to be frozen and a refrigerant is introduced into the coils *E'* by way of the pipe *E*, when ice will be formed in the said sections on the sides of the 70 cells *D*. Then the refrigerant is cut off by means of valve *e* and air is made to enter the fore-cooler *F*, where by lowering its temperature by means of the refrigerant in the coil *E³* any moisture in said air is eliminated. The 75 dry air then enters the pipe *G'* and from thence is led to the various perforated pipes *G²*, from which latter it emerges into the cells *D*, containing the coils *E'*, and by virtue of the perforations *h²* circulates in all portions of the 80 said cells *D*.

The temperature of the air being higher than that of the ice frozen on the outside of the cells, the said ice is detached from the cells, so that it can be removed from the tank, the air 85 being used as a thawing medium.

On the pipe *G* there is fitted a valve *G⁵* or other regulating device to control the volume of air admitted into the fore-cooler *F*, by virtue of which the temperature of the air as it leaves 90 said cooler is regulated, a small amount of air being first allowed to pass through the said cooler, which quantity is augmented during the process of thawing off in the tank, which prevents a too rapid expansion of the metal 95 plates comprising the cells *D*, which expansion is greater than that of the ice.

Having described my invention, I claim—

1. The combination in a freezing-tank, of cells therein, coils for a refrigerant in the cells, 100

a fore-cooling device, pipes for conducting air leading from the fore-cooling device to the said cells, means to regulate the volume of air conducted through the said pipes, and other 5 means to cool the air in the fore-cooler by the refrigerant in the coils.

2. A freezing-tank, cells therein dividing the tank into sections, coils for a refrigerant in the cells, in combination with a fore-cooling 10 device, pipes conveying air connecting the fore-cooling device and the cells, a coil for the refrigerant in the fore-cooler connected with the coils for the refrigerant in the cells.

3. In a freezing-tank; cells dividing the tank 15 into sections to hold the fluid to be frozen; in combination with coils for a refrigerant in the cells; pipes on the outside of the tank to con-

duct a refrigerant through said coils; valves in said pipe; a fore-cooler adjacent to the tank; a coil in the fore-cooler connected with the outlet of the coil in the cells for the refrigerant; an air-pipe leading into the fore-cooler; a valve on said air-pipe; an outlet-pipe in the fore-cooler; perforated pipes in the cells of the tank connected with the air-outlet pipe of the 20 fore-cooler; perforated air-outlet pipes in the cells.

Signed at New York, county and State of New York, this 13th day of April, 1903.

BENJAMIN FRY DALY.
